DIVAN-BED

Melvin E. Roche, Berea, and Hillard J. Sands, Cleveland, Ohio, assignors to Harvard Manufacturing Company

Filed May 14, 1956, Ser. No. 584,870

6 Claims. (Cl. 5—59)

The present invention relates to combination or convertible articles of furniture, such as divan-beds, or the like, and particularly is concerned with the provision of a furniture article wherein a swinging back or bolster support is provided to provide for conversion of the article into a bed, or into a divan, as desired.

Heretofore there have been quite a few different types of combination furniture articles of the general type referred to provided. One of such prior structures is shown in Patent No. 2,645,788 which illustrates one type of a sofa-bed provided with a shiftable back support, while another Patent No. 2,656,548 illustrates another type of a pivotal or removable type of a cushion support member for divan-beds.

In endeavoring to convert divans or sofas or the like into beds, or vice versa, it should be noted that divans should have less depth than a bed requires in width. Hence, it is necessary to provide some type of cushions, bolsters, supports or the like that are positioned on the rear or back portion of the divan-bed when it is in use as a divan, and to remove such cushions, bolsters and/or the supports when the divan-bed is to be used for sleeping purposes. Usually both bolsters and special supports therefor are provided. The bolster support preferably is of a type which will pivot or swing from adjacent a rear portion of the divan-bed forwardly thereof to lessen the effective depth thereof when operatively positioned to adapt the bed for use as a seat or divan.

Structures of the prior art, and similar to that of the present invention, have been relatively expensive to produce, or have not provided the desired type of support action, or they have been somewhat flimsy and weak in structure, or they have been subject to other disadvantages, such as being difficult to move from the divan position over to bed forming position.

Accordingly, it is the general object of the present invention to provide a novel and improved type of a divan-bed article of furniture which is characterized by the provision of a novel support tray and cushion or bolster support member in the divan-bed.

Another object of the invention is to provide an article of furniture of the class described wherein certain bracket support means in the divan-bed can be folded flat substantially into a plane of the lower frame means of the article of furniture for shipping purposes.

A further object of the invention is to use a support shelf in a divan-bed for retaining portions of the structure in an operative position for bolster or cushion support action.

Another object of the invention is to provide a relatively sturdy, inexpensive type of a divan-bed, a shelf and a swing back bracket of which can be readily moved from a cushion or bolster support position to a retracted or inoperative position.

A further object of the invention is to provide a novel combination type of divan and bed which has a special swing back bracket or bolster support member and which

positions a support shelf thereon in either extended operative position or in a folded or collapsed position.

The foregoing and other objects and advantages of the invention will be made more apparent as the specification proceeds.

In the following specification, corresponding articles are referred to by the same number in the drawing and in the specification to facilitate understanding the invention.

10 Reference now should be had to the accompanying drawings, wherein:

Fig. 1 is a perspective view of the swing-back divan-bed of the invention with only the frame means of the structure being shown;

15 Fig. 2 is a fragmentary side elevation, partially broken away and shown in section, of the back support bracket means of the divan-bed and showing the shelf in an elevated or operating position, and the swing-back bracket in the extended or operative position;

20 Fig. 3 is an elevation, similar to Fig. 2, only with the support bracket means being swung to an inoperative or retracted position and the shelf being positioned in its retracted position;

25 Fig. 4 is a fragmentary enlarged plan view of an end portion of the shelf of the divan-bed of the invention and with portions of the shelf being broken away and shown in section for clearness and with an inoperative position of the support bracket means being indicated;

30 Fig. 5 is a perspective view of the divan-bed combination of the invention with mattress, bolsters and the like carried thereon;

Fig. 6 is a view of the divan-bed converted for sleeping purposes into a full size single bed; and

35 Fig. 7 is an enlarged fragmentary view of a rear portion of the divan-bed frame and showing the pivotal connection of the bracket support means thereto, the partially collapsed or folded position of the bracket support member being indicated on dotted lines.

The present invention relates to a divan-bed or the like 40 comprising a frame, a plurality of inverted substantially L-shaped support rods pivotally carried on said frame at the rear portion thereof for pivotal movement of the foot portions thereof from positions extending forwardly of said frame at least to positions extending parallel to a rear frame edge, which support rods terminate in upwardly directed end sections, a bolster support unit carried by said support rod end sections and extending therebetween for unitary movement of said support rods, rear supports carried by the foot portions of said support rods, a tray, and tubular arms pivotally carried by said tray, which is removably supported on said bolster support unit and by said tubular arms engaging said rear supports.

The divan-bed of the invention is indicated as a whole 55 by the numeral 10. This divan-bed includes a suitable metallic frame comprising a front rail 11 and a rear rail 12. Connecting cross rail sections 13 are suitably secured to both of the front rail and rear rails adjacent the ends thereof and extend transversely of the frame, being secured together in overlapped or telescoped relation by any desired type of a clamp member 16. Preferably each of the cross rail sections 13 has a reinforcing angle or rail 14 associated therewith, and usually fixedly secured thereto. Preferably all of these frame means of the invention are made from conventional metal angle iron which is the structure usually used in frames for beds or the like. Casters, glides or other equivalent support members 15 are carried by the cross rails 13 and reinforcing rails 14 by any conventional securing means.

Vertically extending reinforcing legs 12a are provided 60 on the rear rail 12, while a load support leg or surface 12b is also provided thereon. Likewise, load support legs

or surfaces 13a are provided on the cross rails 13, while dependent reenforcing legs 13b are likewise provided thereon. Similarly the reenforcing rails 14 have upper or top load supporting surfaces 14a and dependent or reinforcing legs 14b provided thereon. The dependent legs 13b and 14b are in contact with each other at the front portion of the frame means of the invention and are secured permanently together for reinforcing purposes by any conventional members.

Adjacent the rear portion of the frame, the reenforcing rails 14 are spaced a short distance from the rail sections 13 thereadjacent for purposes to be described hereinafter in more detail.

The back portion of the divan-bed 10 of the invention includes a positioning bracket or member 17 that is generally of L-shape. The lower portion of this bracket 17 is pivotally received intermediate the cross rail sections 13 adjacent the rear of the frame and the reenforcing rails 14 engaged therewith. A vertically upwardly directed leg 18 is provided on each of the brackets 17. Suitable spacer means or blocks 19 of any desired size are positioned, as by rivets 19a, or in any other desired manner, intermediate these adjacent dependent legs 13b and 14b of the rail means of the frame to secure them together tightly in parallel spaced relation, but yet to permit pivotal action of the positioning member or bracket 17, as described hereinafter. The vertical legs 18 of the positioning brackets 17 have tubular sockets 20 secured thereto, as by welding, and extending vertically upwardly therefrom.

Back forming means for the divan-bed 10 are associated with and carried by the tubular sockets 20 provided at each end of the divan-bed assembly. Thus a swing-back support rod or member, or arm 21, usually made from metal rod, is removably received within the tubular socket 20 and is pivotally supported therein, for example, as by peening over the lower edge of the tubular socket 20, as indicated at 20a in Fig. 2, so that the rod 21 cannot extend therethrough and is rotatable in such tubular socket 20. The positioning rods 21 are of inverted L-shape and have separate fingers 22 extending normally therefrom and welded thereto in the foot portions 21a thereof. The support rod 21 terminates in an upwardly extending finger or end portion 23 that in Fig. 2 is shown as extending or being positioned forwardly with relation to the tubular positioning socket 20. That is the operative position for such rod or arm 21.

A bolster or cushion support tube or rod 25 is provided at the rear portion of the divan-bed, and it is formed into a unit with two vertically extending carrier tubes 26 and 27 adjacent the ends of the bolster support tube 25. These carrier tubes 26 and 27 engage the fingers 23 of the swing-back support rods 21 to make a unit therewith. The carrier tubes 26 and 27 also are provided for aiding in supporting a tray or shelf member 28 horizontally in the divan-bed when the divan-bed is operatively positioned for use as a divan. The bolster support tube 25 preferably is welded to the positioning tubes 26 and 27, and all tube ends may have any conventional end caps thereon.

In order to position the rear part of the support shelf or tray 28, it has a pair of short support tubes 29 pivotally secured thereto. The upper ends of the support fingers 22 are deburred, or are balled or peened over to provide semi-spherical support surfaces for the tubular members 29 which are engaged therewith to complete the support for the tray 28. Preferably the upper ends of these support tubes 29 are flattened as indicated at 29a and are at an angle with relation to the remainder of the tubes, as best shown in Fig. 2. Suitable means, such as rivets or bolts 30, are used for pivotally securing the support tubes 29 to rear portions of the shelf 28. The shelf 28 is shown as being made from a metal sheet, which has downwardly extending flanges 28a with inturned edges

28b provided thereon; such flanges 28a and inturned edges 28b extend inwardly of the shelf 28 a short distance for reinforcement purposes. Spacer sleeves 30a, Fig. 4 are provided on the bolts 30, to space the inner ends of the support tubes 29 from the flange and edge means of the tray. Fig. 2 of the drawings best shows how the shelf 28 can be horizontally positioned for operational use. The front portion of the shelf 28 is swung up and disengaged from contact with the support tubes 26 and 27. At the same time, usually the swing-back bracket support rods 21 are swung through an arc of approximately 90° and the carrier tubes 26 and 27, connected together through the bolster support tube 25, pivot on the upwardly extending fingers 23 of the support rods 21 and move them rearwardly as a unit to permit the tray 29 to fall or swing down to the vertical position illustrated in Fig. 3 and lie parallel to a wall against which the divan-bed is positioned.

Fig. 5 of the drawings clearly illustrates how cushions, 20 or bolsters 31 and 32 can be placed upon a mattress 33 carried by the divan-bed when adapted for use as a divan. At such time, the swing-back brackets or support rods 21a are in their forwardmost, operative positions and effectively reinforce or support the cushions 31 and 32 against any rearward movement and reduce the width of the divan-bed available for seating purposes. Fig. 6 clearly illustrates how these cushions 31 and 32 can be removed and the shelf 28 swung down into a vertical position when the swing-back support rods 21 are swung to their inoperative positions so that the full width of the divan-bed is available for sleeping purposes.

Fig. 2 of the drawings shows that a rubber pad or block 34 can be secured to the lower ends of the tubular sockets 18 to prevent such end portions of the socket 35 from bumping against the wall or otherwise marring any other adjacent furniture.

As another feature of the invention, in order to facilitate shipping the divan-bed frame in compact form, the bolster support means, and specifically the brackets 17 are pivotally positioned to permit the vertically extending tubular sockets 20 to be swung down into a generally horizontal position substantially in the plane defined by the horizontal support surfaces 14a and 13a of the reenforcing rails 14 and cross rails 13. Usually in shipping the 40 divan-bed, a pair of the cross rail sections 13 are pivotally secured to the front rail 11 and are swung into alignment therewith for shipping purposes. Such cross rail sections then would be swung out to extend normally from the front rail and be fixedly secured (bolted) in the positions 45 shown.

In shipping the divan-bed 10, as a feature of the invention, a unit is made of the bracket 17, the tubular socket 20, cross rail section 13a, and reenforcing rail 14 for each end of the divan-bed. Fig. 7 shows that a slot 46 is provided in the horizontal leg of each bracket, and bolts, rivets or other means 46a secure the assemblies together. Because of the slots 46, the brackets 17 and sockets 20 can be pulled backwardly and be swung in over the cross rail and reenforcing rail to lay superimposed thereover 50 to provide a compact shipping assembly. Securing a bolt 47 or the like to the assembly when the bracket 17 is swung up to operative position fixes the assembly for use. The clamps 16 next can be positioned to secure the associated cross rail sections together. The rear rail 12 can be bolted or otherwise secured to the rear cross rail sections 55 13a and reenforcing rails 14 after the brackets 17 are operatively positioned.

Fig. 4 of the drawings illustrates that the inwardly extending edge flanges or lips 28b provided on the tray 28 are removed at the front corners of this support shelf or tray so that the support tubes 26 and 27 can be received in the corners of the tray. This locks the tubes 26 and 27 and tray 28 in place and aids in operatively positioning the tray and bolster support means to prevent any undesired swinging movement of the tray and swing-back

rod supports 21 from their operative or assembled position.

The divan-bed of the invention can be readily converted from use as a divan over for use as a bed and when in use as a divan, the tray 28 can support any desired articles thereon, while the bolsters or cushions 31 extend sufficiently laterally of the bed to give it the proper depth for seating action.

The divan frame can be shipped in compact form and be readily assembled by unskilled labor. The divan provides storage space for articles normally desired near a divan and it effectively positions the support tray when not in use. Thus it is thought that the objects of the invention have been achieved.

While one complete embodiment of the invention has been disclosed herein, it will be appreciated that modification of this particular embodiment of the invention may be resorted to without departing from the scope of the invention as defined in the appended claims.

We claim:

1. In a divan-bed or the like, frame means, a tubular socket secured to said frame means and extending vertically adjacent each end of said frame means at a back edge thereof, bolster support means pivotally received in said sockets, said bolster support means providing spaced pairs of vertically upwardly extending support fingers adjacent each end of the divan-bed, a bolster support unit including a pair of upwardly directed support members and being carried by a finger of each of said pairs of fingers to make a unit of said bolster support means and extending the length of said frame means, and a horizontal support tray carried by the said support fingers and bolster support unit.

2. A divan-bed as in claim 1, in which said horizontal support tray has depending lips thereon engaging the upwardly directed support members of said bolster support unit to hold said bolster support means securely in a forward position.

3. In a divan-bed or the like, a frame, a plurality of inverted substantially L-shaped support rods pivotally carried on said frame at the rear portion thereof for pivotal movement of the foot portions thereof from positions extending forwardly of said frame at least to positions extending parallel to a rear frame edge, said support rods terminating in upwardly directed end sections, a bolster support unit carried by said support rod end sections and extending therebetween for unitary movement of said support rods, rear support fingers carried by the foot portions of said support rods and extending upwardly therefrom, a tray, and tubular arms pivotally carried by said tray, said tray being operatively supported on said bolster support unit and by said tubular arms telescopically engaging said rear support fingers.

4. In a divan-bed or the like, frame means, bolster support units extending up from rear portions of said frame means and including pivotal support means, pairs of support fingers operatively carried by said pivotal support means at each end of the divan-bed, and a support member carried by said support fingers, said support member having inwardly extending flange means thereon recessed for engaging one of said support fingers engag-

ing each end of said support member to lock said pivotal support means in operative position.

5. In a swing back divan-bed combination, frame means for said divan-bed comprising a front and a rear rail and cross rails forming a rectangular unit, said rear rail and front rail combining to define a plane, a pair of back rest bracket means carried by spaced rear portions of said frame means and extending vertically thereof, said back rest bracket means having sections movable to and from operative position with relation to said framing means, connecting means carried by and extending between the movable sections of said back rest bracket means to provide a bolster support for the divan-bed combination, said cross rails each include pairs of parallel members and a spacer secured between portions of said parallel members, said bracket means each have an arm extending forwardly therefrom and received between said pairs of parallel members for pivotal movement therebetween, and means securing spaced portions of each of said arms to said cross rails to position said bracket means operatively.

6. In a swing back divan-bed combination, frame means for said divan-bed comprising a front and a rear rail and cross rails forming a rectangular unit, said rear rail and front rail combining to define a plane, a pair of back rest bracket means carried by spaced rear portions of said frame means and extending vertically thereof, said back rest bracket means having sections movable to and from operative position with relation to said framing means, connecting means carried by and extending between the movable sections of said back rest bracket means to provide a bolster support for the divan-bed combination, said bracket means including an arm extending therefrom for connection to said frame means, said arm having a slot therein to make an elongated pivot point to permit said back rest bracket means to slide outwardly with respect to said frame means and pivot and fold downwardly with respect thereto into substantial superimposed relation to part of said frame means in the folded position, said cross rails each including pairs of parallel members and a spacer secured between said parallel members, said bracket means arm being received between said pairs of parallel members for limited pivotal movement therebetween, and means securing spaced portions of each of said arms to said cross rails to position said bracket means operatively.
